GEORGE LEMAUX, OF INDIANAPOLIS, INDIANA, ASSIGNOR TO INDIANAPOLIS BRUSH & BROOM MANUFACTURING COMPANY, OF INDIANAPOLIS, INDIANA, A CORPORATION.

METAL-CASE-BROOM PRESS.

1,151,480.

Specification of Letters Patent. Patented Aug. 24, 1915.

Application filed December 26, 1913. Serial No. 808,908.

To all whom it may concern:

Be it known that I, GEORGE LEMAUX, a citizen of the United States, and a resident of Indianapolis, county of Marion, and State 5 of Indiana, have invented a certain new and useful Metal-Case-Broom Press; and I do hereby declare that the following is a full, clear, and exact description thereof, reference being had to the accompanying drawings, in which like letters refer to like parts.

10 The object of this invention is to facilitate the manufacture of metal case brooms.

A metal case broom is one about the upper portion of which there is a metal case which 15 is secured by nails passing through the broom and metal case on both sides of the broom and clamping said metal case on the broom. As a rule heretofore metal case brooms have been nailed on an open bench 20 where they are clamped by a hand or foot operated clamp and the nails driven through the same, one at a time, against a metal surface which clenches the points of the nails back on the case. One difficulty in making 25 a broom in this manner is that the pressure is brought down by the hammer or other means with great force on each nail separately and hence the heads of the nails are liable to break through the thin metal case.

30 One feature of this invention is to provide means for simultaneously clenching all of the nails in the metal case broom and thereby exerting a similar pressure at the same time on all of the nail heads for avoiding the 35 result above mentioned.

Another feature of the invention consists 40 in yieldingly mounting a beam or lever in connection with a bed plate or machine with suitable dies or clamps on said parts for clenching all of the nails in the metal case broom simultaneously and thus avoiding any 45 injury to the machine resulting from brooms varying in thickness.

The full nature of the invention will be 50 understood from the accompanying drawings and the following description and claims.

In the drawings, Figure 1 is an elevation 55 of said machine. Fig. 2 is a central vertical section through portions thereof. Fig. 3 is a perspective view of one of the dies or clamping plates.

In the machine herein shown there is a 60 bed plate 10 supported on legs 11 and 12. 55 In the form shown in Figs. 1 and 2, a lower

die or clamping plate 13 is mounted on the right-hand end of said bed plate between ribs or lugs 14 and so as to be absolutely rigid in position. The lower die or clamping plate is yieldingly mounted by reason of 60 an opening 15 being provided in the bed plate large enough to permit the die to move downward or upward therein and providing a couple of rods 16 which extend downward from the die 13 through a cross bar 17 below 65 the bed plate and nuts 18 on the lower ends of said rods. Said rods also have washers 19 between their ends and spiral springs 20 lie between said washers and the cross bar 17 and yieldingly support the die 13. These 70 springs should be relatively very strong so as to sufficiently clamp the broom and yet be capable of yielding under an excess of pressure so as to relieve the other parts of the machine of undue strain calculated to 75 break or destroy the same.

The upper die or clamping plate 22 is secured under and to the right-hand end of a walking beam or lever 23 which is fulcrumed between its ends by a pin 24 extending through the ears 25 on the upper end of a rod 26 which passes through a cross bar 27 in the bed plate, as shown in Fig. 2. A spiral spring 28 is mounted on said rod 26 and lies between said cross bar 27 and a washer 29 on the lower end of said rod. This yieldingly holds down the rod 26 and the fulcrum of said beam, and the spring 28 should be very strong so as not to yield excepting when the pressure becomes so great 85 as to be liable to injure the machinery.

The beam 23 is actuated by an eccentric strap 30 surrounding an eccentric wheel 31 on a shaft 32 mounted in the bearings 33 on the bed plate of the machine and driven by a gear 34 on said shaft which meshes with a similar gear 35 on a driving shaft 36 mounted in the supports 12 and carrying a fly wheel 37. The eccentric strap 30 has a slide 40 integral therewith, as shown in Fig. 2, which is slidably mounted in connection with a guideway 41 extending longitudinally of the beam 23 on the underside. As the machine operates, the part 40 slides to and fro 95 longitudinally of the beam and actuates the same.

In operation the nails are first driven through the metal case broom, but not clenched, and thereafter the metal case broom is placed in this machine between the 100 105 110

dies 13 and 22 and all of the nails simultaneously clenched. The machine continuously operates and one broom at a time is placed in the machine when the dies are separated and the spring 28 permits the beam to yield and the spring 20 permits the lower die to yield to accommodate brooms varying in thickness.

The invention claimed is:

- 10 1. A press for clenching nails in metal case brooms including a bed plate, a beam, means for yieldingly fulcruming said beam between its ends on said bed plate, and clamping dies on said bed plate and beam 15 and shaped to receive and hold the broom while the nails are being clenched.
- 20 2. A metal case broom press including a bed plate, a beam, a rod extending loosely through the bed plate, means on one end of said rod for fulcruming said beam between its ends, and a spring on said rod for tending to hold it and the fulcrum in a downward position for clamping brooms between one end of said beam and the bed plate.
- 25 3. A press for clenching nails in metal case brooms including a bed plate, a beam, a rod extending loosely down through the bed plate, means on the upper end of said rod for fulcruming the beam between its ends,

a spring on said rod for tending to hold it 30 and the fulcrum in a downward position, and clamping dies on said bed plate and beam and shaped to receive and hold the broom while the nails are being clenched.

4. A press for clenching nails in metal 35 case brooms including a bed plate, a beam fulcrumed thereon, a die on said beam, a companion die, rods supporting said companion die and extending through said bed plate, and springs tending to maintain said 40 rods in raised position.

5. A press for clenching nails in metal 45 case brooms including a bed plate, a beam fulcrumed thereon, a die on said beam, a companion die, rods supporting said companion die and extending through said bed plate, and springs tending to maintain said 50 rods in raised position, said bed plate having an opening therein under said yielding die to permit its yielding movement.

In witness whereof, I have hereunto affixed my signature in the presence of the witnesses herein named.

GEORGE LEMAUX.
